[57] CLAIM

The ornamental design for an adjustable interior lighting fixture, as shown and described.

DESCRIPTION

FIG 1 is a top, left side perspective view of an adjustable interior lighting fixture showing my new design; FIG. 2 is a top plan view thereof on a reduced scale; FIG. 3 is a bottom plan view thereof on a reduced scale; FIG. 4 is a front elevational view thereof on a reduced scale;

FIG. 5 is a rear elevational view thereof on a reduced scale;

FIG. 6 is a left side elevational view thereof on a reduced scale;

FIG. 7 is a right side elevational view thereon on a reduced scale;

FIG. 8 is a bottom, front perspective view thereof;

FIG. 9 is a front elevational view of a second embodiment of my new design;

FIG. 10 is a top plan view thereof;

FIG. 11 is a bottom, front perspective view thereof. The adjustable support of the second embodiment is identical to that of the first.
